UNITED STATES PATENT OFFICE

HAROLD J. SMITH, OF ELDON, MISSOURI

DESIGN FOR A FILLING STATION FRONT

Application filed September 19, 1930. Serial No. 37,025. Term of patent 3½ years.

To all whom it may concern:

Be it known that HAROLD J. SMITH, a citizen of the United States of America, residing at Eldon, in the county of Miller and State of Missouri, has invented a new, original, and ornamental Design for Filling Station Front, reference being had to the accompanying drawings, forming part thereof.

Figure 1 is a perspective view of a filling station front showing my new design.

Figure 2 is a front elevational view with the pumps omitted; and

Figure 3 is a top plan view with the pumps omitted.

I claim:

The ornamental design for a filling station front, as shown.

In testimony whereof I affix my signature.

HAROLD J. SMITH.
